UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,135, dated March 6, 1888.

Application filed January 26, 1888. Serial No. 262,058. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of rose-shaped flower forms and long arching leaf forms, with short portions of a thick stem-work appearing at intervals, and with smaller stems and leaves pro-

jecting into the intervening spaces. The large 20 leaf forms are deeply serrated. They are ornamented with an overlying stem-and-leaf work of a smaller character, sometimes resembling fern-leaves and sometimes resembling vine leaves and stems. Some of the larger 25 leaves are ornamented with a vein-like work. Along the stems and portions of the leaves is a succession of fine stems or projections resembling moss or lichen work.

What I claim as new, and desire to secure 30 by Letters Patent, is—

The design for carpets, consisting of the design substantially as shown.

JAS. L. FOLSOM.
